UNITED STATES PATENT OFFICE.

WILLIAM C. GHOLSON, OF CINCINNATI, OHIO, ASSIGNOR OF ONE-HALF TO
CHARLES L. DOUGHTY, OF SAME PLACE.

FENCE-MACHINE.

SPECIFICATION forming part of Letters Patent No. 379,458, dated March 13, 1888.

Application filed July 22, 1887. Serial No. 245,019. (No model.)

To all whom it may concern:

Be it known that I, WILLIAM C. GHOLSON, a citizen of the United States, residing at Cincinnati, in the county of Hamilton and State 5 of Ohio, have invented certain new and useful Improvements in Fence-Machines; and I do hereby declare the following to be a full, clear, and exact description of the invention, such as will enable others skilled in the art to which 10 it appertains to make and use the same.

My invention relates to machines for making wire fences of the character in which warning plates or slats are woven into twisted wire. One kind of such "warning-plates" and their 15 position in a wire fence is illustrated in my patent, No. 353,129, of November 23, 1886.

The object of my invention is to dispense with the complicated mechanism heretofore used in many machines and to construct a simple, easily-operated, and efficient machine for the purposes mentioned.

My invention is illustrated in the accompanying drawings, in which—

Figure 1 is a front elevation; Fig. 2, a plan; 25 Fig. 3, a section on line *x x* of Fig. 1, and Fig. 4 a detail.

Referring to the drawings, the frame of the machine is composed of four longitudinal bars, A A A' A', supported between four upright bars, B B B B, and mounted upon uprights C, or other suitable support. Within this frame are placed two racks, D D', an upper and a lower one, each of which is secured to and between two bars, E. The back of each 30 rack-bar extends beyond the bars E and between the bars A. The racks and their carrying-bars E are adapted to be slid in opposite directions between the bars A, as herein-after described.

40 F F are cog-wheels placed between the racks and meshing therewith. These wheels have no axles, but are provided with two or more holes, *g*, each adapted to receive a separate strand of wire. The racks are so placed between the bars E that the bases of their teeth 45 are below the bars, so that the cogs F, when engaging with the racks, are held upon the frame and are prevented from falling out.

H is a cog-wheel mounted in a frame, I, on 50 the machine, connected with a suitable shaft

and crank to be operated by hand or other power, and engaging with the racks to give the same alternate reciprocating motion.

L L represent wires proceeding from reels (not shown) extending through tension-plates 55 N on bars N', and each wire passed through a hole, *g*, in the wheels F. The wheels F are to be placed a distance apart on the racks in accordance with the distance apart it is desired to twist the wire on each plate or slat. 60

The operation of the machine is as follows: The wires being placed in position and extending through the holes *g* in the wheels F (the holes in the said wheels to be increased with the number of wires, as desired) and connected 65 to a drawing reel or drum of ordinary form, (not shown,) the crank is turned, which moves the rack in opposite directions, while the cog-wheels remain and rotate in their respective positions. A first or preliminary twist—such 70 as *p*, for instance—is given. Then the machine is stopped and a slat or warning-plate is placed on the wires between the strands, the motion of the machine reversed, and a twist formed on the opposite side of the plate or slat, another plate or slat is inserted, and the operation 75 is repeated. Thus the order of twisting will be reversed between each plate or slat, and the wire between the tension-bars and the cogs will twist and untwist with the opposite revolution of the wheels while the operation of weaving proceeds.

The number of wire-twisting wheels F may be varied to suit the number of slats or plates to be operated on at the same time. The racks 85 must be of sufficient length to permit of the revolution of the cogs a sufficient number of times to give the desired amount of twist.

The frame and rack-bars may be extended to any desired length, so as to make the fencing at many points throughout the extent of a long room or building. As the wheels twisting the wire carry only their own weight, the force necessary to turn the wheel operating the racks, and at great speed, is not great; but 90 other methods of operating the same than the one I have illustrated may be employed. For instance, shafting may be applied at the opposite ends of the racks to give each its opposite reciprocating motion. 100

The principle of my invention may be adapted to twisting other material than wire and for other purposes than weaving therewith slats and plates.

5 Having thus described my invention, what I claim is—

1. The combination, in a suitable frame, of the racks adapted to move simultaneously in opposite directions and independently of the 10 supporting frame, and the twisting-wheels engaging with said racks and provided with holes through which the twisting material is carried, substantially as and for the purpose described.

15 2. In a wire-fence machine, the combination

of the racks, the sliding bars in which said racks are secured, the stationary bars between which said sliding bars are moved, the axleless cog-wheels held between and engaging with said racks, and suitable mechanism for operating said racks and their supporting-bars simultaneously in opposite directions, substantially as described. 20

In testimony whereof I affix my signature in presence of two witnesses.

WILLIAM C. GHOLSON.
